DISHWASHER BRUSH OR THE LIKE

Ray Rice Hutcheson, Belleville, N. J.

Application January 9, 1957, Serial No. 44,450

Term of patent 14 years

(Cl. D9—2)

Fig. 1 is a bottom plan view of the dishwasher brush or the like, showing my new design;

Fig. 2 is a top plan view;

Fig. 3 is a side elevational view;

Fig. 4 is an end elevational view;

Fig. 5 is a transverse sectional view on line 5—5 of Fig. 2; and

Fig. 6 is a transverse sectional view on line 6—6 of Fig. 2.

I claim:

The ornamental design for a dishwasher brush or the like, as shown.
